RAILWAY TRAFFIC CONTROLLING APPARATUS

Earl M. Allen, Swissdale, and Henry S. Young, Wilkinsburg, Pa., assignors to The Union Switch & Signal Company, Swissvale, Pa., a corporation of Pennsylvania

Application October 4, 1940, Serial No. 359,700

16 Claims. (Cl. 246—134)

Our invention relates to railway traffic controlling apparatus, and it has particular reference to the organization of such apparatus into novel and improved railway traffic controlling systems for controlling the operation of either or both railway signals and track switches.

Interlocking systems heretofore proposed for controlling either or both railway signals and track switches ordinarily incorporate approach locking means rendered effective upon the approach of a train to prevent alteration of the route established for such train. Such systems incorporate means for effecting a normal or "track circuit" release of such approach locking when the train accepts the established route, and also incorporate means for effecting a time release of such locking after enforcing a predetermined time delay. Where "call-on" signals are incorporated into such interlocking systems, it has been customary to maintain such approach locking effective when a "call-on" signal is displayed by utilizing a stick relay controlled by the "call-on" signal lever or button and retained energized over a stick circuit controlled by the control relay of the "call-on" signal. Such systems rely upon the integrity of the stick circuit of the call-on control relay, since ordinarily no means is provided for checking the holding circuit of the call-on control relay and if such circuit should fail, the stick relay might release to permit an improper release of the approach locking when the "call-on" signal is being displayed.

In view of the foregoing and other important considerations, it is an object of our present invention to provide a railway traffic controlling system of the above described class incorporating novel and improved means for positively maintaining the approach locking when a "call-on" signal is being displayed.

Another object of our invention is to provide a remote control or interlocking system of the class described above and incorporating novel and improved means including a polarized relay for maintaining the approach locking when a "call-on" signal is being displayed.

A further object of our invention is to incorporate into a system of the class described, novel and improved means controlled by such polarized relay for preventing a time delay in the release of the approach locking when a slow speed route is established but the slow speed or "call-on" signal does not clear.

An additional object of our invention is to incorporate such polarized relay in a system of the

5 class described, in such a manner as to obtain progressive signaling whereby after a "call-on" signal has been cleared, a high speed signal may be cleared automatically instead of the "call-on" signal in the event that traffic conditions alter to permit such high speed signal.

Another object is to provide such progressive signaling in a railway traffic controlling system in such manner that after a train accepts a high 10 speed signal which has been substituted for a "call-on" signal, the "call-on" signal will not reappear automatically but will be displayed only if the operator takes the steps necessary to clear such "call-on" signal.

15 An additional object is to provide a railway traffic controlling system wherein there is introduced into the control of high speed and slow speed signals a polarized relay arranged to check the route which each signal governs.

20 A further object is to provide an improved railway traffic controlling system wherein there is incorporated into the control of a high speed signal a polarized relay controlled by traffic conditions in the section associated with such signal, whereby track circuit control or "slotting" 25 of such signal is attained.

Another object of our invention is to provide an improved railway traffic controlling system having novel and improved means for providing long and short time releases with checking contacts to check the return of the time element device to normal after the employment of either the long or short time release.

30 A further object of our invention is to provide 35 a system of the class described wherein novel and improved means is provided to prevent a track circuit release of the approach locking when a slow speed signal is employed as a "call-on" signal, but which permits such track circuit release of the approach locking when the slow speed signal is employed for a diverging route.

Another object of our invention is to provide 40 a system of the class described wherein novel and improved means is provided to enable the approach locking relay to pick up without a time delay in the event that the operator fails to restore the signal lever to its normal position when a train accepts a signal.

45 The above-mentioned and other important objects and characteristic features of our invention which will appear as the description proceeds, are attained by incorporating a polarized relay into a railway traffic controlling system of the class described. The polarized relay is con-

trolled by switch repeater relays, track circuits, signal control lever contacts and by the "call-on" lever or push button in such manner as to be energized in a normal direction only when traffic and track conditions are favorable for a high speed signal to be cleared, and to be energized in its reverse position whenever a signal is cleared under conditions unfavorable for a high speed signal.

Other important features of the use of the polarized relay reside in the specific arrangement and organization of the circuits controlled by such relay. We shall describe a preferred form of apparatus embodying our invention, and shall then point out the novel features of our invention in claims.

The accompanying drawing is a diagrammatic view illustrating a preferred form of apparatus embodying our invention.

Referring to the drawing, the diagram at the top represents a stretch of railway track comprising a track section $1T$ intermediate an approach section $A2T$ and another section $O2T$. Each section is provided with the usual closed circuit track circuit including a normally energized track relay as indicated diagrammatically in the drawing, these relays being designated by the reference characters $1TR$, $A2TR$ and $O2TR$, respectively. Section $1T$ also includes a track switch 1 connecting a passing or siding track 4 to section $1T$, and another switch 3 which connects a diverging track 5 to section $1T$.

Switch 1 is actuated by a power operated switch mechanism $1SM$ controlled in the usual manner, not shown, and is provided with a polarized switch repeater relay $1WPR$ controlled over, pole changing contacts 7 and 8 associated with mechanism $1SM$, to a normal position in which the relay is shown, when switch 1 is normal and to a reverse position when the switch is reversed. Similarly, switch 3 is operated by a power actuated switch mechanism $3SM$ also controlled in the usual manner, not shown, and has associated therewith a polarized switch repeater relay $3WPR$ controlled to normal and reverse positions in accordance with the normal and reverse positions of the switch as indicated by movable pole changing contacts 7 and 8 associated with mechanism $3SM$. In order to simplify the drawing, we have omitted showing the circuit which controls the operation of switch mechanisms $1SM$ and $3SM$, but it is to be understood that such circuits in accordance with the usual practice are controlled by an approach locking relay $2RASR$, hereinafter referred to in detail, in such manner that operation of the switches may be effected when and only when relay $2RASR$ is picked up.

The movement of traffic on the main track into section $1T$ in the normal direction from left to right as viewed in the drawing is governed by a signal $2R$ comprising a high speed signal unit $2RA$ which normally indicates stop but which may be cleared to indicate proceed when sections $1T$ and $O2T$ are unoccupied and switches 1 and 3 are normal; and an auxiliary slow speed or "call-on" signal unit $2RC$ which may be cleared to permit a train operating in the normal direction of traffic on the main track to enter section $1T$ when switch 3 is reversed and/or section $1T$ or $O2T$ is occupied by a preceding train. The movement of traffic from track 4 into section $1T$ is controlled by a signal $2RD$ which may be cleared when switch 1 is reversed. The movement of traffic on the main track into section $1T$ against the normal direction of traffic

is controlled by a slow speed signal $2LA$, which may be cleared if switch 3 is normal; and the movement of traffic from track 5 into section $1T$ is governed by a signal $2LB$ which may be cleared when switch 3 is reversed.

The above-mentioned signals may be of any desired type, but as illustrated in the drawing are searchlight signals which may, for example, be of the type disclosed and covered in Letters

Patent of the United States, No. 1,864,224, granted to Wesley B. Wells on June 21, 1932, for Light signals. Signal unit $2RA$, for example, comprises an armature 15 mounted to rotate between an intermediate position to which it is biased, and at least one extreme position. Armature 15 is controlled by an armature winding 16 , and is arranged in such manner that when the winding is energized, the armature will rotate clockwise to its right-hand extreme position. Attached to armature 15 to rotate therewith are at least two colored roundels G and R , which are arranged to be disposed in the path of a beam of light projected from an associated lamp 17 according as the armature 15 occupies its right-hand extreme position or its intermediate position. For convenience in illustration, lamp 17 in the drawing is shown disposed above the associated roundels, but it will readily be understood that in actual practice lamp 17 will be located directly back of the associated roundels, and will have associated therewith a suitable optical system, not shown, for projecting a beam of light from the lamp.

Signal $2RA$ indicates "stop" or "proceed" according as roundel R or roundel G is in front of its associated lamp 17 when this lamp is lighted. Operatively connected with armature 15 is a circuit controller comprising two movable contact fingers 18 and 19 . The movable contact finger 18 cooperates with a fixed contact $18b$ to close a contact $18-18b$ when armature 15 occupies its intermediate position, but which contact is opened when armature 15 occupies its right-hand position; while movable contact member 19 cooperates with a fixed contact $19b$ to close a contact $19-19b$ in both the intermediate and the right-hand positions of armature 15 . Other movable contact members 20 and 21 are controlled by armature 15 to close contacts $20-20b$ and $21-21b$ in the intermediate position of armature 15 , contact $20-20b$ being opened when armature 15 is in its right-hand position.

The signal lamps 17 may be either normally dark as shown and approach lighted; or if desired such lamps may be normally illuminated. We have not shown in the drawing the circuits over which lamps 17 of the several signals are approach energized, but it is to be understood that such lamps are energized by circuits controlled in the usual manner whereby there is attained approach lighting of the signals.

Control of the signals is established through the medium of a manually operable control lever V , which may, for example, be a signal control lever of an interlocking machine located at a point remote from the signals. Lever V normally occupies a normal position N , and is movable to one extreme position R to condition the control apparatus, hereinafter described in detail, to establish control over signal $2R$ or $2RD$; and to another extreme position L wherein the control apparatus is conditioned to control signal $2LA$ or $2LB$. Lever V is provided with a plurality of circuit controlling contacts, each selectively

closed in accordance with the position of the lever. Each contact of lever V bears one or more reference characters N, R or L, to indicate the different positions of the lever in which such contact is closed. For example, contact 47 of lever V bears the reference character NL to indicate that this contact is closed when the lever is in or intermediate its normal N and left L positions; while contact 49 of the lever bears the reference character NR to indicate that such latter contact is closed whenever the lever is in or intermediate its normal N and right R positions. In order to simplify the drawing, certain of the lever contacts are shown located remote from the lever, but in each case such contacts have been identified by the reference character of the lever operating such contacts; by an identifying reference character referring to the particular contact in question; and by the reference character N, R or L designating the positions of the lever in which such contacts are closed.

Associated with signals 2R and 2RD there is a polarized control relay 2RHR of the type which retains its polar armature in its last operated position. Relay 2RHR is energized in its normal direction when and only when conditions are safe for signal 2RA to display its "proceed" indication. Such conditions exist if switches 1 and 3 are normal and sections 1T and 02T are unoccupied, as will be made clear presently. With switch 3 reversed; or with switch 3 normal and switch 1 reversed; or with both switches normal, section 1T and/or 02T occupied, lever V in its right position R, and a manually operable push button COPB actuated, relay 2RHR is energized in its reverse direction in a manner to be explained as the description proceeds.

Also associated with signals 2R and 2RD is an approach locking relay 2RASR, and associated with this relay are a time element relay 2RTER, a repeater relay 2RNTEPR, and a slow releasing stick relay 2RTESR. Relay 2RASR is normally energized when signal units 2RA, 2RC and 2RD are at stop, lever V is normal, and section A2T is unoccupied. Alternate paths controlled by relays 2RHR, 1TR and 2RTESR are provided in the circuit of relay 2RASR, and these alternate paths will be pointed out in detail when the circuit of relay 2RASR is traced hereinafter.

The time element relay 2RTER may be of any suitable type such as, for example, the thermal relay illustrated and described in Letters Patent of the United States, No. 2,114,895, granted on April 19, 1938, to Harry E. Ashworth for Thermal relay. Relay 2RTER is provided with a thermal element 24 effective to close a time contact 25 at the end of a predetermined interval of time after energization of the relay, and with a checking contact 26 which opens shortly after the energization of the relay and closes only when time contact 25 assumes its normal position. Relay 2RTER is normally deenergized so that checking contact 26 is closed to complete for relay 2RNTEPR an obvious energizing circuit, which circuit becomes opened to release relay 2RNTEPR upon energization of relay 2RTER over a circuit controlled by back contact 45 of relay 2RASR and signal units 2RA, 2RC and 2RD at stop. After time contact 25 of relay 2RTER closes, relay 2RTESR becomes picked up over a circuit which includes time contact 25 of relay 2RTER; and relay 2RTESR also is provided with a stick circuit path including its own front contact 80 which shunts time contact 25 of relay 2RTER.

Signals 2LA and 2LD also are provided with

an approach locking relay 2LASR and a time element relay 2LTER, which relays correspond in functions to relays 2RASR and 2RTER, but the circuits for relays 2LASR and 2LTER have been omitted in order to simplify the drawing.

In order further to simplify the drawing, we have represented relay contacts at times disposed remote from the relays which cause them to operate, but in each case such contacts bear the reference characters identifying not only the respective relay operating such contacts but also a number individual to each of such contacts. For example, the reference character 1TR has been placed immediately above front contact 28 to indicate that this contact is operated by relay 1TR, and this contact has been represented closed to indicate that relay 1TR is normally energized.

The apparatus is in its normal condition, as represented in the drawing, when sections A2T, 1T and 02T are unoccupied and switches 1 and 3 are locked in their respective normal positions. In this normal condition of the apparatus, all signals are conditioned to display their "stop" indications; lever V is in its normal position N; and relay 2RHR is energized in its normal direction over a circuit extending from one terminal B of a suitable source of current, such as a split battery 46 having a mid terminal C and two opposite terminals A and B, through front contact 28 of relay 1TR, front contact 29 of relay 02TR, normal polar contact 30-31 and front contact 32 of relay 1WPR, normal polar contact 33-34 and front contact 35 of relay 3WPR and the winding of relay 2RHR to a common terminal C of the course of current. Approach locking relay 2RASR also is energized over its normal circuit which may be traced from terminal B through contacts 18-18b and 19b-19 of signal units 2RD, 2RC and 2RA, respectively, contact 37 of lever V, front contact 38 and normal polar contact 39-40 of relay 1WPR, front contact 41 of relay A2TR, front contact 42 of relay 2RNTEPR, normal polar contact 43-44 of relay 2RHR, and the winding of relay 2RASR to terminal C. With relay 2RASR energized, its front contact 45 is closed to complete an obvious stick circuit path around the contacts of relays 1WPR, A2TR, 2RNTEPR and 2RHR interposed in its just traced normal circuit. Also, relays 2RTER and 2RTESR are released, but relay 2RNTEPR is energized over the circuit including normally closed checking contact 26 of relay 2RTER.

To clear signal unit 2RA of signal 2R for a train operating over the main track in the normal direction of traffic, the operator moves lever V to its right position R, thereby opening at contact 37 of lever V the previously traced normal energizing circuit of relay 2RASR, which relay thereupon releases, and closing at contact 53 of lever V a "proceed" circuit for unit 2RA of signal 2R, which circuit may be traced from terminal B through front contact 48 of approach locking relay 2LASR provided for signals 2L, contact 49 of lever V, front contact 50 of relay 3WPR, front contact 51 of relay 1WPR, back contact 52 of relay 2RTESR, lever contact 53, back contact 54 of relay 2RASR, normal polar contact 55-56 and front contact 57 of relay 2RHR, and winding 16 of signal unit 2RA to terminal C. Signal unit 2RA is now conditioned to display its "proceed" indication, and if lamp 17 of unit 2RA of signal 2R becomes approach energized due to the approach of a train, signal unit 2RA will display its "proceed" indication.

It is to be noted that the route established for the train, and traffic conditions in advance of such route, are evidenced by polarized relay 2RHR, which must be energized in its normal direction in order that high speed signal unit 2RA might be cleared. Inasmuch as contacts of the switch repeater relays 1WPR and 3WPR are introduced into the circuits of relay 2RHR as well as into the signal control circuit, it is evident that improper routing such as might be caused by crosses, grounds, etc., are protected against in much the same manner as that heretofore obtained in a two-wire, double break system wherein wires of the signal control circuit extending to both terminals of the operating source of current are carried through contacts of the control apparatus.

When the approaching train occupies section A2T, relay A2TR releases to open front contact 41 in the normal circuit of relay 2RASR, and when the train occupies section 1T, relay 1TR releases to open front contact 28 and thereby open the normal energizing circuit of relay 2RHR. The releasing of relay 2RHR of course causes its front contact 57 to open and thus open the previously traced "proceed" circuit of signal unit 2RA, whereupon that signal unit automatically goes to "stop," and back contact 60 of relay 2RHR closes to complete around lever contact 37 in the normal circuit of relay 2RASR an alternate path. Back contact 61 of relay 1TR is now closed and completes around front contact 38 and normal polar contact 39-40 of relay 1WPR and front contact 41 of relay A2TR, which latter contact is open with the train in approach section A2T, an alternate path in the circuit of relay 2RASR, and it follows that when the train occupies section 1T and signal unit 2RA automatically goes to "stop," relay 2RASR is caused to pick up regardless of whether lever V is restored to its normal position or not, over a circuit extending from terminal B through contacts 18-19b and 19-19b of signal units 2RA, 2RC and 2RD, respectively, back contact 60 of relay 2RHR, back contact 61 of relay 1TR, front contact 42 of relay 2RNTEPR, normal polar contact 43-44 of relay 2RHR and the winding of relay 2RASR to terminal C. It is, of course, obvious that if the operator properly restores the lever to its normal position after the train enters section 1T, lever contact 37 is closed in multiple with back contact 60 of relay 2RHR in the just traced circuit of relay 2RASR. It follows that track circuit release of the approach locking is effected when a train accepts the proceed indication of signal unit 2RA.

In the event that switch 3 is reversed, operation of lever V to its R position will clear slow speed signal unit 2RC of signal 2R or signal unit 2RD according as switch 1 is in its normal or reverse position respectively. That is to say, with switch 3 reversed to cause relay 3WPR to operate to its reverse position, the previously traced normal circuit of relay 2RHR is opened at normal polar contact 33-34 of relay 3WPR and an obvious reverse energizing circuit is completed for relay 2RHR extending from terminal A of the source of current through reverse polar contact 62-34 and front contact 35 of relay 3WPR and the winding of relay 2RHR to terminal C. With relay 2RHR energized in its reverse direction, the opening of lever contact 37 when the lever is operated to its R position and the consequent release of relay 2RASR to close its back contact 54, completes a circuit for signal

unit 2RC or 2RD, which circuit corresponds to the circuit previously traced for signal 2RA up to polar contact member 55 of relay 2RHR, and then extends from that member through reverse polar contact 55-63 of relay 2RHR, front contact 64 of relay 2RNTEPR, then either through reverse polar contact 65-67 of relay 1WPR closed if switch 1 is reversed, and winding 16 of signal unit 2RD to terminal C to clear signal unit 2RD, or through normal polar contact 65-66 of relay 1WPR closed if switch 1 is normal, contacts 21-21b and 20-20b of signal unit 2RA closed when that unit is at stop, and winding 16 of signal unit 2RC to terminal C to clear the latter signal unit. As the train passes cleared signal unit 2RC or 2RD, as the case may be, the signal unit remains in its clear position but may be restored to stop by the operator restoring lever V to its normal position N. When this is done, contact 53 of lever V opens to cause the circuit of signal unit 2RC or 2RD, as the case may be, to become opened, and such unit accordingly assumes its stop position wherein there is completed for relay 2RASR a circuit extending from terminal B through contacts 18-18b and 19-19b of signal units 2RD, 2RC and 2RA, respectively, lever contact 37, back contact 61 of relay 1TR, front contact 14 and reverse polar contact 73-44 of relay 2RHR and the winding of relay 2RASR to terminal C, and relay 2RASR accordingly picks up to complete its stick circuit at front contact 45, thereby releasing the approach locking of the apparatus.

In the event that a train occupies section 1T and/or 02T to put unit 2RA to stop, and it is desired under such conditions to signal a following train to enter section 1T, the operator moves lever V to its R position, and then actuates the manually operable push button COPB. This causes relay 2RHR to be energized in its reverse direction over a circuit extending from terminal A through contact 70 of lever V, contact 71 of push button COPB, back contact 29 of relay 02TR or back contact 28 of relay 1TR and front contact 29 of relay 02TR, normal polar contact 39-31 and front contact 32 of relay 1WPR, normal polar contact 33-34 and front contact 35 of relay 3WPR, and the winding of relay 2RHR to terminal C, and relay 2RHR is caused to operate its polar contact members to their reverse positions. Push button COPB may now be released, and slow speed or "call-on" signal unit 2RC clears over its previously traced circuit, due to the fact that with lever V operated to its R position to open contact 37, relay 2RASR was caused to release to open its front contact 45 when relay 2RHR became energized to open back contact 60 during the interval that push button COPB was actuated. It should be noted that signal unit 2RC will not clear under the above assumed conditions unless the route is proper, that is, unless switches 1 and 3 are normal. It should further be noted that although relay 2RHR becomes released in its reverse position when push button COPB is released, and relay 2RHR closes its back contact 60 to shunt around open lever contact 37, relay 2RASR remains released since normal polar contact 43-44 of relay 2RHR is now open and both front contacts 14 and 75 of relays 2RHR and 2RTESR, respectively, through which relay 2RASR might be energized, are open. Furthermore, with relay 2RASR retained released to close its back contact 54, a signal unit 2RC is caused to display its "proceed" indication to thereby cause contact 19-19b of

unit 2RC to be opened until such time as the following train accepts the signal and the operator restores lever V to its normal position, unless the preceding train vacates sections 1T and 02T prior to the following train accepting the slow speed "call-on" signal indication. In this latter event, relays 1TR and 02TR of course pick up to complete the normal energizing circuit of relay 2RHR, which thereupon becomes energized in its normal direction to complete at normal polar contact 55-56 the previously traced "proceed" circuit of signal unit 2RA, and to control unit 2RC to "stop." With unit 2RA cleared and relay 2RHR operated to its normal position, it is apparent that when the following train accepts the "proceed" indication of signal unit 2RA and enters section 1T, unit 2RA is controlled to its "stop" indication, and the slow speed indication of unit 2RC does not reappear unless the operator again actuates push button COPB.

Our invention also provides means for obtaining a long or a short time release for the approach locking according as the route attempted to be altered is a high speed or a slow speed route. Such time releases of the approach locking are of course utilized to insure that once a route has been established for an approaching train, such route cannot be altered to a lower speed route until after the elapse of a predetermined time interval sufficient to enable the speed of the train to be reduced from that permitted under the first established route to that permitted under the altered route. It is thus evident that if the train is approaching a cleared high speed signal at a high rate of speed, such train requires a relatively longer time in which to be brought to a stop or to a slow speed than does the train approaching a cleared slow speed signal at a low speed, hence it is desirable to establish for a train a relatively long or a relatively short time release according as the signal under which the train has been proceeding is a high speed or a slow speed signal.

Assume now that with signal unit 2RA cleared to indicate "proceed" and with a train in section A2T, the operator wishes to alter the route established for the train. Under such assumed conditions, relay 2RHR is energized in its normal direction, and relay 2RASR is released, as pointed out previously. To alter the established route, the operator moves lever V to its normal position, thereby opening at lever contact 53 the previously traced "proceed" circuit of signal unit 2RA, which unit accordingly goes to stop and thus completes for time element relay 2RTER an energizing circuit which extends from terminal B through contacts 18-18b and 19-19b of signal units 2RD, 2RC and 2RA, respectively, lever contact 37, back contact 45 of relay 2RASR, back contact 80 of relay 2RTESR, and heating element 24 of relay 2RTER to terminal C. The energization of relay 2RTER causes its checking contact 26 to open and thus deenergize relay 2RNTEPR, so that when time contact 25 of relay 2RTER closes at the end of the predetermined time interval of relay 2RTER, stick relay 2RTESR is picked up in multiple with relay 2RTER over a circuit corresponding to the circuit of relay 2RTER up to the heel of contact 80 of relay 2RTESR, and then passing through time contact 25 of relay 2RTER, back contact 81 of relay 2RNTEPR and the winding of relay 2RTESR to terminal C. Relay 2RTESR thereupon picks up to open its back contact 80 and thus open the previously traced energizing cir-

cuit of relay 2RTER, and to complete a stick circuit over its closed front contact 80. Relay 2RTESR remains energized over its stick circuit until the cooling of heating element 24 of relay 2RTER causes checking contact 26 to close and complete the circuit of relay 2RNTEPR. When this happens, relay 2RNTEPR picks up to cause relay 2RASR to pick up over a circuit extending from terminal B through contacts 18-18b and 19-19b of signal units 2RD, 2RC and 2RA, respectively, contact 37 of lever V, front contact 75 of relay 2RTESR, front contact 74 of relay 2RHR, front contact 42 of relay 2RNTEPR, normal polar contact 43-44 of relay 2RHR and the winding of relay 2RHR to terminal C. When relay 2RASR picks up, its back contact 45 becomes opened to open the stick circuit of relay 2RTESR, which relay thereupon drops at the end of its slow release period, and front contact 45 of relay 2RASR completes for that relay its stick circuit which holds that relay energized after relay 2RTESR drops and opens its front contact 75 interposed in the last traced pick-up circuit of relay 2RASR.

With approach locking relay 2RASR picked up, the operator may now operate switch 1 and/or 3 to the reverse position and thus alter the route which had been established for the train approaching signal unit 2RA. For example, if switch 3 is reversed by the operator, relay 3WPR of course will be operated to its reverse position to energize relay 2RHR to its corresponding reverse position, and the operator may now signal the train to take the diverging track by operating lever V to its right position R, thus causing relay 2RASR to release and close its back contact 54 and thereby in turn clearing signal 2RC by completing the previously traced circuit of this unit since reverse polar contact 55-53 of relay 2RHR is now closed. This circuit over which signal unit 2RC is cleared checks against improper switch closure in much the same manner as that pointed out hereinbefore that relay 2RHR checks the circuit of signal unit 2RA. That is to say, if relay 2RHR is operated to its reverse position upon reversal of switch 3, the switch must remain in its full closed reverse position in order that relay 2RHR may be energized and unit 2RC may be cleared. In the event that switch 3 creeps open, relay 3WPR releases to open its front contact 50 interposed in the previously traced circuit of unit 2RC to prevent the clearing of that signal unit when lever V is operated to its right position R, and also to open front contact 35 interposed in the reverse energizing circuit of relay 2RHR. With relay 2RHR released to close its back contact 60, the opening of lever contact 37 interposed in the previously traced normal circuit of relay 2RASR does not cause that relay to release and impose the approach locking on the apparatus, hence the operator may restore lever V to its normal position if he sees that signal unit 2RC does not clear, and is enabled to establish another route for the train without requiring the approach locking to be released through the medium of time element relay 2RTER. It follows, therefore, that the use of back contact 60 of relay 2RHR in the circuit of relay 2RASR enables an operator at times to change a route quickly in the event that the route that he has attempted to establish cannot properly be obtained.

The short time release is provided by apparatus embodying our invention when the operator wishes to alter a route established for a train

governed by slow speed signal units 2RC or 2RD. Under such assumed conditions, that is, with a slow speed signal unit cleared, relay 2RHR is in its reverse position and relay 2RASR is released. The operator first puts the slow speed signal unit to "stop" when he restores lever V to its normal position to open lever contact 53, and after the signal unit assumes its stop position, relay 2RTER is energized over its previously traced energizing circuit in the manner explained heretofore. The energization of relay 2RTER causes relay 2RNTEPR to release upon the opening of checking contact 26, as pointed out hereinbefore, and when time contact 25 of relay 2RTER closes at the end of its predetermined time interval, relay 2RTESR is picked up over its previously traced pick-up circuit. When this happens, front contact 75 of relay 2RTESR completes for relay 2RASR a pick-up circuit which extends from terminal B through contacts 18-18b and 19-19b of signal units 2RD, 2RC and 2RA, respectively, lever contact 37, front contact 75 of relay 2RTESR, reverse polar contact 73-44 of relay 2RHR, and the winding of relay 2RASR to terminal C, and relay 2RASR accordingly picks up to close its front contact 45 and thus close its stick circuit which holds that relay energized when relay 2RTESR releases due to the interruption of its stick circuit at back contact 45 of relay 2RASR. With relay 2RASR picked up, the operator may now alter the previously established route.

It should be noted that the short time release is provided when time contact 25 of relay 2RTER closes, thus differing from the long time release which utilizes both the heating and cooling time of relay 2RTER, that is, it requires that the heating time of the relay be utilized to close contact 25 and then that the cooling time of the relay be employed to close checking contact 26 prior to effecting the energization of approach locking relay 2RASR. This long time release is of course self-checking in that the release cannot be established until after the time element relay is restored to its normal position as indicated by checking contact 26, hence there is avoided the possibility that a failure of time contact 25 to return to its normal position might enable a subsequent operation of the time element relay to be completed in less than its predetermined time interval.

When the short time release is utilized, equivalent checking of the normal position of the time element relay is obtained by introducing into the control of all signals which are afforded a short time release, a contact controlled by relay 2RTER in its normal position. Thus, for example, the normal position of relay 2RTER is checked by interposing front contact 64 of relay 2RNTEPR, which relay is energized only if relay 2RTER occupies its normal position as indicated by the closure of checking contact 26, in the clearing circuits of signal unit 2RC or 2RD. It follows that if time contact 25 of relay 2RTER fails to return to its normal position but instead returns to a position such that another energization of the relay will close contact 25 in a time shorter than its predetermined time interval, contact 26 of the relay of course will not close, relay 2RNTEPR will remain released, and contact 64 of relay 2RNTEPR will remain open to prevent the clearing of signal unit 2RC or 2RD.

In the event that signal unit 2RC is cleared as a "call-on" signal with a preceding train in section 1T or O2T, and the following train accepts

the "call-on" signal and enters section 1T, relay 2RASR remains released and the approach locking accordingly remains effective for the short time release interval since under the conditions assumed, relay 2RHR is in its reverse position and is deenergized with call-on push button COPB released. It follows that although all signals are at stop, relay 2RASR remains deenergized since normal polar contact 44-43 of relay 2RHR is open, and front contact 74 of relay 2RHR and front contact 75 of relay 2RTESR are also open. Relay 2RTESR, however, becomes energized at the end of the heating period of relay 2RTER due to the fact that under the assumed conditions the previously traced energizing circuit of relay 2RTER is completed at back contact 45 of relay 2RASR, and after relay 2RTESR picks up, its front contact 75 closes to complete an obvious circuit for relay 2RASR, which circuit includes contact 75 of relay 2RTESR and reverse polar contact 73-44 of relay 2RHR. The energization of relay 2RASR of course releases the approach locking.

If, however, signal unit 2RC is cleared as a slow speed signal for a diverging move from section 1T into diverging track 5, then switch 3 and repeater relay 3WPR are reversed and relay 2RHR is energized in its reverse position so that when the train accepts signal 2RC and enters

section 1T, the approach locking may be released by restoring lever V to its normal position wherein lever contact 37 is closed to complete a circuit for relay 2RASR extending from terminal B through contacts 18-18b and 19-19b of signal unit 2RD, 2RC and 2RA, respectively, lever contact 37, back contact 61 of relay 1TR, front contact 74 of relay 2RHR and reverse polar contact 73-44 of relay 2RHR and the winding of relay 2RASR to terminal C.

From the foregoing, it is readily apparent that signals and/or switches are controlled in accordance with our invention by means of a very simple arrangement of circuits which involve a polarized relay 2RHR. The use of this relay enables the main line signals to be "slotted," that is, such signals are placed under the control of traffic on the main line track. By incorporating contacts of the switch repeating relays in the circuits of this relay as well as in the signal control circuits, protection substantially equivalent to a double wire, double break system is afforded against improper routing caused by crosses, grounds, etc. Also, the circuits involving the polarized relay 2RHR are arranged to prevent a track circuit release of the approach locking when the slow speed signal unit 2RC is employed as a "call-on" signal, but which permits such track circuit release when the slow speed signal is employed to signal a diverging route. In addition, the use of relay 2RHR permits progressive signaling in that if slow speed signal unit 2RC has been cleared as a "call-on" signal and traffic conditions in advance change to permit the display of the high speed signal, signal unit 2RC automatically goes to "stop" and high speed signal unit 2RA automatically clears if the following train has not accepted the "call-on" signal. This progressive signaling feature, moreover, is effected while enforcing stick signaling principles on the "call-on" signal, in that after the "call-on" signal has been released due to the clearing of the high speed signal in response to traffic conditions on the main track, the "call-on" signal cannot be displayed automatically when the following train accepts the

high speed signal, but rather to restore the "call-on" signal it is necessary for the operator again to actuate the call-on push button. Furthermore, the polarized relay 2RHR is incorporated into circuits which provide both long and short time releases for the approach locking, and wherein the return of a timing device to its normal position is checked for each long and short time release operation. In addition, the polarized relay permits the approach locking to be released in the regular manner for a high speed main track move even though the operator might neglect to restore the signal lever to its normal position.

Although we have herein shown and described only one form of railway traffic controlling apparatus embodying our invention, it is to be understood that various changes and modifications may be made therein within the scope of the appended claims without departing from the spirit and scope of our invention.

Having thus described our invention, what we claim is:

1. In combination, a stretch of railway track including a track switch for establishing a high speed or a diverging route, a signal indicating proceed, slow speed or stop for governing the movement of traffic over said routes, a polarized relay, means for energizing said relay in one direction over a circuit controlled by traffic on said stretch and by said switch and effective when traffic and switch conditions are suitable for the high speed route, other means for energizing said relay in the opposite direction when said switch is set for the diverging route, manually controllable means also effective when said switch is set for the high speed route but traffic conditions on said stretch are unfavorable for such route for energizing said polarized relay in said opposite direction, and means for controlling the signal to its proceed or its slow speed indication according as said relay is energized in its said one direction or is in its opposite position.

2. In combination, a stretch of railway track including a track switch for establishing a high speed or a diverging route, a signal indicating proceed, slow speed or stop for governing the movement of traffic over said routes, a polarized relay, means for energizing said relay in one direction over a circuit controlled by traffic on said stretch and by said switch and effective when conditions are safe for said high speed route to be established, other means for energizing said relay in the opposite direction when said switch is set for the diverging route, manually controllable means effective when said switch is set for the high speed route but traffic conditions on said stretch are unfavorable for such route for energizing said polarized relay in said opposite direction, circuit means for conditioning said signal to display its proceed or its slow speed indication according as said relay is energized in its said one direction or is in its opposite direction, and manually controllable means for rendering said circuit means active.

3. In combination, a stretch of railway track including a track switch, a signal for governing traffic over said stretch and switch, said signal normally indicating stop but operable to display proceed and slow speed indications, a polarized relay, means for energizing said relay in one direction over a circuit controlled by traffic conditions on said stretch and by said switch and effective only when traffic and switch conditions

are favorable for the display of the proceed indication of said signal, other means effective when the condition of said switch is favorable for said proceed indication but traffic conditions in said stretch are unfavorable for such indication for conditioning said relay to be energized in its other direction for operating the relay to its reverse position, manually controllable means for rendering said other means active, and manually controllable means for operating said signal to its proceed or its slow speed indication according as said relay is energized in said one direction or is in its reverse position.

4. In combination, a stretch of railway track including a track switch, a signal for governing traffic over said stretch and switch, said signal normally indicating stop but operable to display proceed and slow speed indications, manually operable means effective in one position for controlling said signal to its stop indication and in another position for conditioning said signal to display its proceed or slow speed indication, a polarized relay, means controlled by said manually operable means for energizing said relay in one direction over a circuit controlled by traffic conditions on said stretch and by said switch and effective only when traffic and switch conditions are favorable for the display of the proceed indication of said signal, other means effective when the condition of said switch is unfavorable for the display of said proceed indication for conditioning said relay to be energized in its other direction for operating the relay to its reverse position, other manually controllable means for energizing said relay in its other direction when traffic conditions are unfavorable for the display of said proceed indication, and means for controlling said signal to its proceed or its slow speed indication according as said relay is energized in said one direction or is in its reverse position.

5. In combination, a stretch of railway track including a track switch, a main signal indicating proceed, slow speed or stop for governing the movement of traffic over the stretch, another signal governing the movement of traffic into said stretch over said switch, a first relay having two positions one corresponding to traffic movements over said stretch and the other corresponding to traffic movements into said stretch over said switch, a polarized relay, circuit means for normally energizing said polarized relay in one direction controlled by said first relay and by traffic conditions in said stretch, other circuit means manually controllable when said stretch is occupied for energizing said polarized relay in the other direction, means governed by said first relay for operating said polarized relay to its other direction when said switch is set for traffic movements into said stretch, and circuit means controlled by said first relay and by said polarized relay for causing said main signal to indicate proceed or slow speed according as said polarized relay is energized in one direction or the other respectively and for causing said other signal to display proceed when both said first relay and said polarized relay occupy their respective other positions.

6. In combination, a stretch of railway track including a track switch, a signal indicating proceed, slow speed and stop for governing the movement of traffic over the stretch, a polarized relay, means for energizing said relay in one direction over a circuit controlled by traffic on said stretch and by said track switch and effective when traffic and switch conditions are safe for said signal

to indicate proceed, means for energizing said relay in its other direction over a circuit controlled by traffic on said stretch and by said track switch and effective when traffic and switch conditions are unsafe for the signal to indicate proceed, means controlled by said relay for conditioning said signal to indicate proceed or slow speed according as said relay is in its said one or said other position, locking means rendered effective upon the approach of a train to the switch for preventing operation thereof, and means including a polar contact of said relay for at times rendering said locking means ineffective.

7. In combination, a stretch of railway track including a track switch, a detector track circuit for said switch, a polarized relay, means for energizing said relay in one direction over a circuit controlled by traffic on said stretch and the position of said switch and effective when conditions are favorable for a high speed move over said stretch, means for energizing said relay in its other direction over a circuit controlled by traffic on said stretch and the position of said switch and effective when conditions are unfavorable for a high speed move over said stretch and said switch is conditioned for a high speed move, locking means rendered active upon the approach of a train to said switch for preventing operation thereof, and means rendered effective when said detector track circuit is occupied and controlled by said polarized relay for immediately rendering said locking means inactive when said polarized relay is in its said one direction but not when it is in its said other direction.

8. In combination, a stretch of railway track including a track switch, a polarized relay, means for energizing said relay in one direction over a circuit controlled by traffic on said stretch and the position of said switch and effective when conditions are favorable for a high speed move over said stretch, means for energizing said relay in its other direction over a circuit controlled by traffic on said stretch and the position of said switch and effective when traffic conditions are unfavorable for a high speed move over said stretch and said switch is conditioned for a high speed move, locking means rendered active upon the approach of a train to said switch for preventing operation thereof, and means controlled by traffic on said stretch adjacent said switch and including a polar contact of said relay for immediately rendering said locking means inactive when said relay is in its said one position and for rendering said locking means inactive at the end of a predetermined time interval when said relay is in its said other position.

9. In combination, a stretch of railway track including a track switch, a polarized relay, means for energizing said relay in one direction over a circuit controlled by traffic on said stretch and the position of said switch and effective when conditions are favorable for a high speed move over said stretch, means for energizing said relay in its other direction over a circuit controlled by traffic on said stretch and the position of said switch and effective when traffic conditions are unfavorable for a high speed move over said stretch and said switch is set for a high speed move, locking means rendered active upon the approach of a train to said switch for preventing operation thereof, and means responsive to a train on said stretch adjacent said switch for rendering said locking means immediately inactive when said relay is in its said one posi-

tion but not when said relay is in its said other position.

10. In combination, a stretch of railway track including a track switch, a repeater relay controlled by said track switch, a polarized relay, circuit means controlled by traffic in said stretch and by said repeater relay for energizing said polarized relay in one direction when conditions are favorable for a high speed move through the stretch, other circuit means controlled by traffic in said stretch and by said repeater relay for conditioning said polarized relay to be energized in its other direction when conditions require a low speed movement in said stretch, locking means rendered active upon the approach of a train to said switch for preventing operation thereof, means responsive to the entrance of the train on said stretch and including a polar contact of said polarized relay closed in its said one direction or a front contact and a polar contact of said polarized relay closed in its other direction for rendering said locking means inactive for train moves through said section but not over said switch.

11. In a traffic controlling system for railroads, the combination with a section of track provided with a track circuit and including a track switch, a high-speed signal and a low-speed signal governing traffic over said switch, of a polarized relay, means controlled by the position of said switch for energizing said relay with current of one relative polarity or the other according as said switch is set for a high-speed movement and said track circuit is unoccupied, or said switch is set for a low-speed movement, other means for energizing said relay with current of said other polarity when said switch is set for a high-speed movement and said track circuit is occupied, and means for clearing said high-speed signal or said low-speed signal according as said relay is energized by current of said one or said other polarity.

12. In a traffic controlling system for railroads, the combination with a section of track provided with a track circuit and including a track switch, a high-speed signal and a low-speed signal governing traffic over said switch, of a polarized relay, means controlled by the position of said switch for energizing said relay with current of one relative polarity or the other according as said switch is set for a high-speed movement and said track circuit is unoccupied, or said switch is set for a low-speed movement, other means for energizing said relay with current of said other polarity when said switch is set for a high-speed movement and said track circuit is occupied, and means also controlled by the position of said switch for clearing said high-speed signal or said low-speed signal according as said relay is energized by current of said one or said other polarity.

13. In a traffic controlling system for railroads, the combination with a stretch of track including a track switch, a track circuit for a section in advance of said switch, and a high-speed signal and a low-speed signal governing traffic over the switch, of a polarized relay, means for energizing said relay in one direction when said track circuit is unoccupied and said switch is set for a high-speed movement and for energizing said relay in the opposite direction when said switch is set for a low-speed movement, other means for energizing said relay in said opposite direction when said track circuit is occupied and said switch is set for a high-speed movement,

and means for governing said high-speed signal or said low-speed signal according as said relay is energized in its said one or said opposite direction.

14. In a traffic controlling system for railroads, the combination of a section of track provided with a track circuit and including a track switch, a high-speed signal and a low-speed signal governing traffic over the switch, of a polarized relay, manually operable means for energizing said polarized relay in one direction when said track is unoccupied and said switch is positioned for a high-speed movement and for energizing said polarized relay in the opposite direction when said switch is positioned for a low-speed movement, other means for energizing said polarized relay in its said opposite direction when said track circuit is occupied and said switch is positioned for a high-speed movement, manually operable means for clearing said high-speed signal or said low-speed signal according as said polarized relay is energized in its said one or said opposite direction, switch locking means rendered effective when either signal is cleared to prevent operation of said switch, a time measuring device for releasing said locking means under certain traffic conditions at the end of a measured time interval after a signal is manually put to stop, and means including a polar contact of said polarized relay for causing said time interval to be relatively long when said high-speed signal is put to stop and to be relatively short when said slow-speed signal is put to stop.

15. In combination with a detector section of railway track including a track switch, a section in approach of said section, a polarized relay of the type that retains its polar contacts in their last energized position, means for energizing said polarized relay with current of normal polarity when said detector section is unoccupied and said switch is set for a high-speed movement and for energizing said polarized relay with current of reverse polarity when said switch is set for a low-speed movement, manually operable means for momentarily energizing said polarized relay with current of said reverse polarity when said detector section is occupied and said switch is set for a high-speed movement, a locking relay which when deenergized prevents operation of said switch, a circuit for energizing said locking relay when said detector

section is occupied and including a normal polar contact, or a reverse polar contact and a front contact of said polarized relay, and another circuit for energizing said locking relay including a reverse polar contact of said polarized relay and completed only at the end of a measured time interval after said detector section becomes occupied.

16. In combination with a detector section of railway track including a track switch, a section in approach of said section, a high-speed signal and a low-speed signal governing traffic from said approach section over said switch, a polarized relay of the type that retains its polar contacts in their last energized position, means for energizing said polarized relay with current of normal polarity when said detector section is unoccupied and said switch is set for a high-speed movement and for energizing said polarized relay with current of reverse polarity when said switch is set for a low-speed movement, manually operable means for momentarily energizing said polarized relay with current of said reverse polarity when said detector section is occupied and said switch is set for a high-speed movement, manually operable means for clearing said high-speed signal or said low-speed signal according as their polar contacts of said polarized relay are in their normal or reverse positions respectively, a locking relay which when deenergized prevents operation of said switch, time measuring means for measuring two predetermined time intervals, a circuit effective if said approach section is occupied when a signal is manually put to stop and including a polar contact of said polarized relay, for energizing said locking relay at the end of the longer or the shorter of said two predetermined time intervals according as said polar contact is in its normal or in its reverse position, a circuit for energizing said locking relay when said detector section is occupied and including a normal polar contact, or a reverse polar contact and a front contact of said polarized relay, and another circuit for energizing said locking relay including a reverse polar contact of said polarized relay and completed only at the end of a measured time interval after said detector section becomes occupied.

CERTIFICATE OF CORRECTION.

Patent No. 2,287,078.

June 23, 1942.

EARL M. ALLEN, ET AL.

It is hereby certified that error appears in the printed specification of the above numbered patent requiring correction as follows: Page 9, second column, line 28, claim 16, for "their" read --the--; line 30, same claim, for "when when" read --which when--; and that the said Letters Patent should be read with this correction therein that the same may conform to the record of the case in the Patent Office.

Signed and sealed this 4th day of August, A. D. 1942.

Henry Van Arsdale,
Acting Commissioner of Patents.
